Charles F. Gaunt,
Inventor,

William L. Keat

Attorney.

UNITED STATES PATENT OFFICE.

CHARLES F. GAUNT, OF BIRMINGHAM, ENGLAND.

DEVICE FOR ATTACHING MEDALS AND THE LIKE TO THE PERSON.

Application filed November 16, 1923. Serial No. 675,036.

To all whom it may concern:

Be it known that I, CHARLES FREDERICK GAUNT, of Warstone Parade Works, Birmingham, England, a subject of the King 5 of Great Britain, have invented certain new and useful Improvements in Devices for Attaching Medals and the like to the Person; and I do hereby declare that the following is a full, clear, and exact description 10 thereof.

My invention has for its object to provide a device in the nature of a clip or holder to detachably retain a medal, badge or other article of adornment or decoration 15 without in any way cutting or otherwise disfiguring the article.

The invention may be said briefly to consist of a holder or clip consisting of a resilient ring adapted to be opened to receive the medal, badge or the like and firmly hold the same, means for attaching the holder to the person being pivotally or otherwise fastened to the holder.

For full comprehension, however, of my 25 invention reference must be had to the accompanying drawings in which similar reference characters indicate the same parts and wherein:

Figure 1 is a plan view of my clip or 30 holder with a medal set in place;

Figure 2 is a transverse vertical sectional view taken on line 2—2 Figure 1 without a medal in place; and

Figure 3 is a detail elevation of the clip 35 or holder without a medal in place.

The clip constituting the preferred embodiment of my holder consists of thin sheet metal formed to present an open circular ring or frame of substantially angular cross section and with its axial wall 2 slightly concaved. The back 3 is preferably flat and has an enlargement 4 near its middle, such enlargement having a flat integral tongue 5 bent in the form of a hook 40 which is passed through an eye 7 on the upper end of a pin 6, the eye being formed by bending the pin at right angles to its main length in loop form.

This frame or holder permits a medal 50 such as indicated at 8 to be sprung into it where it may be held without disfigurement on either side the inherent resiliency of the frame retaining the medal without the aid

of extraneous means. The wearer may insert a medal or badge bearing the representation of a baseball player or other pictorial or embossed representation and thus wear it during the event of which the medal is emblematic. And afterwards the medal or badge not being in any way disfigured 60 on either side may be taken out and preserved and the holder or frame used for other emblems or medals.

What I claim is as follows:

1. A clip or holder adapted to receive 65 and detachably retain a medal or the like, the said clip or holder consisting of a resilient open ring adapted to receive and retain the medal or the like, the resiliency of the ring being sufficient to retain the 70 medal without the aid of extraneous means.

2. A clip or holder adapted to receive 75 and detachably retain a medal or the like, the said clip or holder consisting of a resilient open ring adapted to receive and 80 retain the medal or the like, the resiliency of the ring being sufficient to retain the medal without the aid of extraneous means and such ring having an integral flat back coextensive with the ring and a pin for attachment to the person.

3. A clip or holder adapted to receive 85 and detachably retain a medal or the like, said clip or holder consisting of a resilient open ring adapted to receive and retain the medal without overlapping the front face thereof.

4. A clip or holder adapted to receive 90 and detachably retain a medal or the like, the said clip or holder consisting of a resilient open ring adapted to receive and retain the medal or the like, the resiliency of the ring being sufficient to retain the medal without the aid of extraneous means and such ring having an integral flat back 95 coextensive with the ring and the said back having an integral hook upon which is pivoted a pin for attachment to the person.

5. A clip or holder adapted to receive 100 and detachably retain a medal or the like, the said clip or holder consisting of a resilient open ring adapted to receive and retain the medal or the like, the resiliency of the ring being sufficient to retain the medal without the aid of extraneous means, 105 the ring being of angular cross-section, the

peripheral wall of the ring being concaved and the back wall having an extension with an integral tongue bent to hook form, and a pin having an eye bent at right angles to the main length of the pin and connected to the tongue.

5 In testimony whereof I have signed my

name to this specification in the presence of two witnesses.

CHARLES F. GAUNT.

Witnesses:

GORDON G. COOKE,

HARRIETTE McDONALD.
